UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

AMPLIFYING APPARATUS.

Application filed July 1, 1924. Serial No. 723,602.

My invention relates to amplifying apparatus, and particularly to amplifying apparatus including a three element electron tube.

5 One purpose of my invention is to provide an arrangement of apparatus which will automatically compensate for variations in the voltage of the uni-directional current supply of a three element electron tube amplifier so that its alternating current output will not be affected by such variation.

I will describe one form and arrangement of apparatus embodying my invention, and will then point out the novel features there- 15 of in claims.

The accompanying drawing is a diagrammatic view showing one form of amplifying apparatus embodying my invention.

Referring to this drawing, the apparatus 20 comprises an electron tube A having a filament 1, a grid 2, and a plate 3. The source of the energy to be amplified is here shown as a winding 4 tuned by a condenser 14 and in inductive relation with a railway track 25 rail 5 in which alternating current is assumed to be flowing.

Filament 1 is supplied with current from a suitable source of direct current, such as a generator G, and a regulating resistance 30 7 is interposed between the negative terminal of generator G and the filament 1. The grid 2, is connected, through winding 4 with resistance 7, this resistance serving to regulate the amount of negative grid bias of the tube A, which negative bias is preferably made greater than the peak value of the alternating current voltage normally supplied by coil 4. Voltage is applied to the plate circuit by a dynamotor D that is, a rotating machine having a low voltage winding 9 and a high voltage winding 8 on the same armature and a field winding 13 for supplying magnetic flux to both windings. The low voltage winding 9 and the field winding 45 13 are connected in parallel with generator G. One terminal of winding 9 is connected directly with filament 1, and the other terminal of this winding is connected, through primary 10 of a transformer T, with plate 3 of tube A. Secondary 11 of transformer T is connected with the device 12 to which it is desired to supply the amplified energy. The device 12 may be a relay, as here shown,

or may be any other suitable form electrical apparatus.

The operation of an electron tube amplifier is well understood by those skilled in the art, and for present purposes it is only necessary to state that the alternating voltage induced in winding 4 is applied to the grid of tube A, is amplified, and causes a current of similar characteristic but increased amplitude to be superposed upon the direct current supplied to the plate circuit by winding 8 of dynamotor D. The alternating component of the current flowing in the plate circuit is transferred to device 12 by transformer T.

Under some conditions of operation considerable fluctuation may occur in the voltage of generator G. With only the apparatus thus far described, this fluctuation would have three results. First, it would vary the temperature of filament 1; second, it would vary the negative bias of grid 2; and third, it would vary the speed of dynamotor D and hence the output voltage of winding 8. All three of these things would vary the amount of alternating current supplied to device 12.

This is undesirable, and to prevent its occurrence I interpose a ballast lamp 6 between resistance 7 and filament 1. This lamp may comprise an iron wire filament in a low pressure hydrogen atmosphere, or may be of any suitable type having the characteristic of increasing its electrical resistance with increase of voltage applied thereto, so that it tends to maintain the current through filament 1 and resistance 7 constant over a considerable range of applied voltage. On account of this characteristic, therefore, a given increase in the voltage of generator G will cause a substantially equal increase in the voltage drop across ballast lamp 6, and in the negative bias of grid 2 with respect to filament 1, because the ballast lamp is in the circuit between grid 2 and filament 1.

Dynamotor D is preferably so wound that its turn ratio, that is, the ratio of the turns in windings 9 and 8, is substantially equal to the amplification constant of tube A.

I will assume that the apparatus is so proportioned and adjusted as to give proper operation at normal voltage of generator G, and that the tube A has an amplification

constant of 8. If now the voltage of generator G varies, as by an increase of one volt, the ballast lamp 6 will maintain a constant current through the filament 1 and the negative bias of grid 2 will be increased by one volt. This will manifestly tend to decrease the plate potential by an amount equal to the change in grid bias multiplied by the amplification constant of the tube, that is, 10 eight volts. But the increase of one volt in the electromotive force of generator G also tends to increase the voltage of winding 8 of dynamotor D by eight volts and hence the decrease caused by the increased negative grid bias compensates for the increased voltage delivered by the dynamotor and the resultant voltage applied to the plate circuit of the tube therefore remains substantially constant. Since also the filament current remains constant, it follows that the direct current in the plate circuit, and in consequence, the alternating current output of the tube for a given input voltage likewise remains substantially constant.

25 The operation of the apparatus when the voltage of generator G falls below normal is just the converse of that described above, and will be understood without further explanation.

30 It is evident that it is not essential that the dynamotor turn-ratio be exactly the same as the amplification constant of the tube, but that an advantageous compensation will be provided by this arrangement of apparatus in greater or less degree whatever the relation between these two factors may be.

35 Amplifying apparatus embodying my invention is particularly adapted for, though in no way limited to, application to railway traffic controlling apparatus in which train carried governing mechanism is controlled by energy received from the trackway.

40 Although I have herein shown and described only one form of amplifying appa-

ratus embodying my invention, it is understood that various changes and modifications may be made therein within the scope of the appended claims without departing from the spirit and scope of my invention.

Having thus described my invention, what I claim is:

1. In combination, an electron tube, a source of direct current voltage connected with the filament of said tube, a ballast lamp interposed between said filament and the negative terminal of said source, a grid circuit for the tube including said ballast lamp, and a dynamotor energized from said source and having a turn ratio equal to the amplification constant of said tube for supplying voltage to the plate circuit of said tube.

2. In combination, an electron tube, a source of uni-directional filament current, a ballast lamp interposed between the negative terminal of said source and the filament of said tube, a grid circuit for said tube including said ballast lamp, and a dynamotor having one winding connected with said source and a second winding included in the plate circuit of said tube, the dynamotor being so constructed that an increase of one unit in the voltage of said source causes the voltage in the plate circuit to increase by a number of units equal to the amplification constant of said tube.

3. In combination, an electron tube, a source of direct current voltage connected with the filament of said tube, a ballast lamp interposed between said filament and the negative terminal of said source, a grid circuit for the tube including said ballast lamp, and means for supplying the plate circuit of said tube with voltage derived from and proportional to said direct current voltage.

In testimony whereof I affix my signature.

LLOYD V. LEWIS.
